Primary Examiner — Wendy L Arminio*Assistant Examiner* — Mary Claire Nemeth(74) *Attorney, Agent, or Firm* — KIRTON McCONKIE;
Evan R. Witt(57) **CLAIM**

The ornamental design for a power supply, as shown and described.

DESCRIPTION

FIG. 1 is a perspective view of a power supply showing our new design, wherein enlarged view of identified portion 9 is shown in FIG. 9;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged detail view of the power supply as identified in portion 9 of FIG. 1.

The broken lines are for the purpose of illustrating portions of the power supply that form no part of the claimed design. The additional broken line encircling the area of the enlarged detail view shown in FIGS. 1 and 9 denotes the boundary of the enlarged detail view and forms no part of the claimed design.
